UNITED STATES PATENT OFFICE

162,631

VEHICLE LAMP HOUSING OR SIMILAR ARTICLE

Louis J. Diamond, Los Angeles, Calif.

Application January 27, 1950, Serial No. 7,532

Term of patent 7 years

(Cl. D48—32)

To all whom it may concern:

Be it known that I, Louis J. Diamond, a citizen of the United States, residing at Los Angeles, in the county of Los Angeles, State of California, have invented a new, original, and ornamental Design for Vehicle Lamp Housing or Similar Article, of which the following is a specification, reference being had to the accompanying drawing, forming part thereof, in which:

Fig. 1 is a top plan view of a vehicle lamp housing or similar article showing my new design;

Fig. 2 is a front elevational view;

Fig. 3 is a bottom plan; and

Fig. 4 is an end elevation thereof, taken from the right end of Fig. 1, the two ends being symmetrical.

I claim:

The ornamental design for a vehicle lamp housing or similar article, as shown and described.

LOUIS J. DIAMOND.
